UNITED STATES PATENT OFFICE.

GUSTAF E. ANDERSON, OF BROCKTON, MASSACHUSETTS.

BUCKLE-HOLDING ATTACHMENT.

Application filed July 28, 1922. Serial No. 578,109.

To all whom it may concern:

Be it known that I, GUSTAF E. ANDERSON, a citizen of the United States, residing at Brockton, in the county of Plymouth and State of Massachusetts, have invented a new and useful Improvement in Buckle-Holding Attachments, of which the following is a specification, reference being had therein to the accompanying drawings.

10 This invention relates to an attachment for sewing machines which is designed to hold a buckle or other article in proper position while the same is being fastened to suitable material by stitching.

15 In the use of zigzag or button sewing machines for attaching buckles to leather or cloth fabrics, it is customary for the machine operator to position the buckle with the fingers holding it firmly on the material while the machine applies stitches back and forth over the center bar of the buckle. It is somewhat difficult, however, where the positioning of the buckle is done entirely by hand to secure absolute alignment of the buckle with the edge of the material and, therefore, great care is required on the part of the operator in positioning and holding the buckle. This naturally slows down the rapidity of the operation, 30 and at the same time the work is not uniformly satisfactory in appearance.

The main object of the invention is the provision of a buckle holding device of simple construction, which may be easily 35 and expeditiously applied to a sewing machine of the character described, and which when applied will hold a buckle securely in proper position and against displacement while it is being secured to material by 40 stitching.

Another object of the invention is the provision of a device which may be adjusted, both in a longitudinal and a transverse direction, in order to accommodate the device 45 to sewing machines of varying construction and to buckles of various shapes and styles.

Other objects of the invention will be more specifically set forth and described hereinafter.

50 Briefly, my invention in its preferred form contemplates a device, adapted to be temporarily fastened to a suitable part of a sewing machine, such as, for instance, the presser-bar, and provided with resilient

gripping means formed to receive and hold 55 a buckle in proper position for attachment to material; said gripping means being so arranged as to be adjustable in two directions, longitudinally and transversely the device. One of the important features of 60 my invention resides in the longitudinal adjustment. Since it is generally necessary in attaching a buckle to material to use two sets of stitches across the center bar, one set on each side of the tongue, the buckle 65 must, after the first set of stitches is applied, be moved into position for the second set. To take care of this contingency I provide adjustable stops for regulating the 70 length of the path of movement of the gripping means, so that the device is placed in engagement with one stop for the first set of stitches, and then after that set of stitches has been applied, the gripping means with 75 the buckle is merely moved into engagement with the other stop. By adjusting the positions of these stops, the device can be quickly changed from one size of buckle to another.

In the drawings illustrating the preferred 80 form of my invention, Figure 1 is a plan view of a device constructed and operated in accordance with my invention; Figure 2 is a side elevation of the same; Figure 3 is a bottom plan view of the same; and Figure 4 is a transverse sectional view of the 85 carrier block showing the means for adjusting the buckle-holding jaws.

In the drawings showing one embodiment 90 of my invention, 10, 10, indicate a pair of jaws pivotally and loosely mounted on two pivot screws 14, threaded into the under side of a carrier block 16; each jaw being bent downwardly and then horizontally, and having its end 18 turned inwardly toward the 95 other jaw. A helical spring 20, having each end turned around a screw 22 set in each one of the jaws, serves normally to draw the two jaws together. To hold the jaws apart against the tension of the spring 20, a screw- 100 pin 24 may be threaded through the carrier block 16 in such location that its cone-shaped end 26 will engage the backs 28 of the jaws 10. The pin 24 may be provided with a knurled head 30 to facilitate handling. 105 When the pin 24 is turned downwardly, its point is forced in between the backs 28, thereby forcing the jaws apart against the

tension of the spring 20. Turning the screw-pin 24 in the opposite direction withdraws its point from between the jaws and permits the spring 20 to draw them together so far as the pin 24 permits.

The ends 18 of the jaws may be grooved at 32 to facilitate the holding of a buckle between them, and a depending guide 34 may be secured to the block 16 by a screw 36, the guide being slotted at 38 to permit adjustment to different-sized buckles.

For mounting the carrier block and its gripping means upon a suitable part of a sewing machine, any means may be provided which will permit of the jaws being adjusted in both a longitudinal and a transverse direction, and one form of such means is shown comprising an arm 40 and a skeleton support 42 carried thereby, upon which the carrier block 16 may be slidably mounted. The block is provided with recesses in its top to receive the two sides of the support 42, and is held thereon by a top plate 43 fastened to the block 16 by screws 45. The arm 40 has its forward end provided with a vertical recess 44 and a through opening 46, whereby it may be mounted on and secured by suitable fastening means to the presser bar of a sewing machine. On the rearward end of the arm 40 is a stub-shaft 48, and the rear end of the support 42 is provided with an integral sleeve 50 to receive said shaft 48. A pin 52 set in an offset portion 54 on the arm 40 passes through a similar offset portion 56 on the sleeve 50 and serves as a guide pin to hold the support against rotation on the shaft 48. For adjusting the sleeve 50 on the shaft 48 and thereby moving the support toward and from the presser-bar, a screw-pin 58 having a knurled head 60 is loosely mounted in an open slot 62 in the offset portion 54 and is threaded through the offset portion 56. An annular flange 64 serves to retain the screw-pin 58 in the same permanent relation to the arm 40, while its rotation causes the support 42 with carrier and jaws to move on the pin 48 either toward or away from the arm 40 according to the direction of rotation of the screw 58.

In view of the fact that it is customary to secure buckles to various materials by two sets of stitches, one on each side of the tongue of the buckle, it is of course necessary to move the buckle and material after the first set of stitches has been applied into position to have the second set of stitches placed; and in order that this movement may be made expeditiously and accurately I provide suitable stops to limit the movement of the carrier block 16 and jaws 10 longitudinally the support 42. In the drawings are shown two knurled head screw-pins 66, one threaded through each end of the support 42 in a longitudinal di-

rection and projecting into the central recess 68 of the support. By turning these two stops in one direction or the other, the path of the block 16 may be lengthened or shortened within the limit of the recess. 70

In the use of my device, it is first secured to a suitable part of the sewing machine, preferably the presser-bar, by any suitable clamping means. In the form shown in the drawings, the arm 40 is provided with the vertical recess 44 to receive the presser-bar and with the opening 46 to receive clamping means. Any suitable means may be used for this purpose, however, and the free end of the arm 40 may be variously shaped to conform to the means used. After being secured in position, the device may then be adjusted to the particular work which it is to do. The screw-pin 24 is turned down to force the jaws 10 apart until separated sufficiently to permit a buckle 72 to be pushed into the end grooves 32 of the jaws. This adjustment should be such that the insertion of the buckle forces the jaws further apart to a slight degree against the tension of the spring 20, so that the buckle is at all times held in position by that pressure. The screw-pin 24 serves the purpose merely of bringing the jaws to a position where a buckle can by slight pressure be forced in between them and held tightly. Otherwise, since the spring 20 would draw the jaws together, the insertion of a buckle would require considerable more trouble on the part of the operator and consume perhaps an appreciable amount of time. At the same time the guide 34 is adjusted in position to be engaged by the inner side of the buckle 72 when between the jaws by loosening and then tightening the screw 36. After these adjustments have been made, the stops 66 should be entirely withdrawn from the recess 68, and the block then moved on the support 42 to bring the inner half of the center bar 74 of the buckle in position to receive the first set of stitches from the needle. This may also require a transverse adjustment of the support on the stub-shaft 48 by manipulation of the screw-pin 58 the stub-shaft 48 being provided with a suitable transverse slot to permit lateral movement of the stop pin 66 which passes through said stub-shaft. When the device has been so adjusted in these two directions that the inner half of the center bar is in position to receive the first set of stitches, the left hand stop 66 may then be turned inwardly to bring its end into engagement with block 16. The foregoing adjustments place the device in its initial position, ready for the first set of stitches. The block 16 should then be moved sufficiently to bring the outer half of the center bar 74 in position to receive the second set of stitches; and while the block is in that position, the right hand stop pin 115

66 should be turned inwardly to bring its end into engagement with the other side of the block.

Thereafter, all that is required in the use 5 of the device is to insert the buckle in the position shown in Figure 1 between the jaws 10 and in engagement with the guide 34; move the block into engagement with one of the stop pins 66; start the machine and apply 10 one set of stitches; then stop the machine; move the block into engagement with the other stop; apply the second set of stitches; and the operation is completed.

It will be observed that by making proper 15 adjustments my device can be used in connection with buckles of all shapes and sizes, and it makes no difference whether the tongue 76 of the buckle and the center bar 74, or either of them, are arranged eccentrically in the buckle. In any event, after 20 the device has been adjusted to the first buckle, it may then be used without limit and without requiring further adjustments upon all buckles of that particular size and 25 shape.

One of the principal advantages of my device is that the buckle will always be secured in an absolutely true position on the material and in perfect alignment with the edge 30 thereof. This is of special advantage in fastening buckles to small belts, for shoe or slipper straps, and in similar cases where absolute alignment of the buckle is required.

35 This result is further contributed to by the fact that, after the insertion of the buckle, both hands of the operator are left free for the operation of the machine and the holding of the material.

40 I further found from my experience that the use of my device, in addition to producing uniform work, greatly increases the amount of work which can be turned out in a given period, thereby reducing the cost of 45 production.

It is to be understood that my invention 50 may be embodied in other forms of construction other than herein shown and described, and is not to be limited to any specific construction except where so limited in the following claims.

What I claim is:

1. A device of the character described 55 having, in combination, an arm adapted for mounting on the presser foot of a zig-zag sewing machine and provided with a transverse stub-shaft, a skeleton support slidably mounted on said stub-shaft and having an offset portion, a screw carried by said arm 60 threaded through said offset portion for moving said support on said stub-shaft, a guide pin for holding said support against rotation on said stub-shaft, a carrier block 65 slidably mounted on said skeleton support and movable in a path at right angles to the

path of movement of said support, a pair of adjustable stops for limiting the movement of said carrier and jaws mounted on said carrier block.

2. A device of the character described 70 having, in combination, an arm adapted to be fixed to the presser foot of a zig-zag sewing machine and provided at its free end with a transverse stub-shaft, a support slidably mounted on said stub-shaft, a screw 75 pin carried by said arm for adjustably moving said support on said stub-shaft, a block slidably mounted on said support, and a pair of jaws pivotally mounted on said block.

3. A device of the character described 80 having, in combination, an arm adapted to be fixed at one end to the presser foot of a zig-zag sewing machine and provided with a transverse stub-shaft, a support mounted on said stub-shaft and movable thereon in a 85 direction parallel with the longitudinal axis thereof, means for moving said support, a block slidably mounted on said support for movement in a direction at right angles to the movement of said support, a pair of jaws 90 pivotally mounted on said block and resilient means for drawing said jaws together.

4. A device of the character described 95 having, in combination, an arm adapted to be fixed at one end to the stationary presser foot of a zig-zag sewing machine and provided with a transverse stub-shaft, a support slidably mounted on said stub-shaft, means for adjustably moving said support on said shaft in a direction at right angles to the 100 normal line of feed of said machine, a block mounted on said support and movable thereon in a direction at right angles to the direction of movement of said support, means for regulating the length and location of 105 the path of movement of said block and pair of jaws carried by said block for holding a buckle or similar object.

5. A device of the character described 110 having, in combination, an arm adapted to be mounted on a stationary presser foot in a sewing machine, said arm being provided with a transverse stub-shaft; a support slidably mounted on said support in a direction transverse to said shaft, a guide pin for holding said support against rotation on said shaft, a carrier block mounted on said support and movable thereon in a direction at right angles to the direction of movement of said support, a pair of jaws 115 on said block for holding a buckle or similar article, resilient means for drawing said jaws together and adjustable means for regulating the distance between said jaws when closed by said resilient means.

6. A device of the character described 120 having, in combination, an arm adapted to be detachably secured to a stationary presser foot in a sewing machine parallel to the normal line of feed and having a transverse 130

- stub-shaft, a support mounted on said stub-shaft, means for adjustably moving said support on said shaft in a direction at right angles to the normal line of feed, a block mounted on said support and movable thereon in a direction parallel to the normal line of feed, adjustable stops for limiting the path of movement of said block in either direction, a pair of jaws carried by said block for holding a buckle or similar article, resilient means for drawing said jaws together and an adjustable screw stop interposed between the rear ends of said jaws for limiting their inward movement.
15. 7. A device of the character described having, in combination, an arm adapted to be detachably secured to the stationary presser foot of a zig-zag sewing machine

and provided at its free end with a transverse stub-shaft and a guide pin, a support 20 slidably mounted on said stub-shaft and guide pin, an adjusting screw for moving said support on said stub-shaft and guide pin in a direction at right angles to said arm, a block slidably mounted on said support in a path parallel to said arm, two adjustable stops for limiting the movement 25 of said block in either direction, a pair of jaws for holding a buckle or similar article, a spring for holding said jaws in closed position and an adjustable stop for limiting the inward position of said jaws.

In witness whereof, I hereunto set my hand this twenty-fifth day of July, 1922.

GUSTAF E. ANDERSON.
